US00D624708S

(12) **United States Design Patent**
Meritt

(10) **Patent No.:** **US D624,708 S**
(45) **Date of Patent:** **** Sep. 28, 2010**

(54) **FEEDER FOR QUAIL OR TURKEY**

(75) Inventor: **Rick Meritt**, Gilmer, TX (US)

GB 2129266 A 5/1984

(73) Assignee: **Rick Meritt Investments, Ltd.**, Gilmer, TX (US)

(Continued)

(**) Term: **14 Years**

(21) Appl. No.: **29/346,303**

(22) Filed: **Oct. 29, 2009**

Related U.S. Application Data

(63) Continuation of application No. 29/296,696, filed on Oct. 25, 2007, now Pat. No. Des. 604,017, which is a continuation of application No. 11/160,611, filed on Jun. 30, 2005, now Pat. No. 7,370,605, which is a continuation-in-part of application No. 09/920,231, filed on Aug. 1, 2001, now Pat. No. 6,920,841.

(57) **CLAIM**

The ornamental design for a feeder for quail or turkey, as shown and described.

DESCRIPTION

FIG. 1 is a perspective view of a feeder for quail or turkey according to my new design;

FIG. 2 is a front elevation view of the feeder for quail or turkey shown in FIG. 1;

FIG. 3 is a rear elevation view of the feeder for quail or turkey shown in FIG. 1;

FIG. 4 is a right side elevation view of the feeder for quail or turkey shown in FIG. 1;

FIG. 5 is a left side elevation view of the feeder for quail or turkey shown in FIG. 1;

FIG. 6 is a top plan view of the feeder for quail or turkey shown in FIG. 1; and,

FIG. 7 is a bottom plan view of the feeder for quail or turkey shown in FIG. 1.

The broken lines are for illustrative purposes only and form no part of the claimed design.

1 Claim, 4 Drawing Sheets
